SEPARABLE HINGE CONSTRUCTION

Abraham Lipman Rubinoff, Toronto, Ontario, Canada, assignor of one per cent to A. H. S. Adams, Toronto, Ontario, Canada

Application September 30, 1949, Serial No. 118,933

3 Claims. (Cl. 16—172)

1

This invention relates to a hinge for hingedly connecting two members together, of the general class having pintles and channeled knuckles which engage with each other, and to a method for hingedly connecting two members together.

Hinges of this general class have been provided in the past. In order to connect two members together with them, however, it has, to my knowledge, always been necessary to connect them first at one point along the edge to be joined, and subsequently to connect them at a spaced apart point. Connecting members in this way is relatively awkward and limits the applicability of the construction.

I have invented a hinge of this class which has a wider applicability.

It is an object of the invention to provide a hinge, the leaves of which can be caused to engage with each other by causing the channeled knuckles to engage with the pintles simultaneously at all points along the edges to be connected, and which will lock together so that disengagement is impossible upon slight rotation.

It is a further object of this invention to provide a hinge having the above-mentioned characteristics which is cheap to manufacture.

With these and other objects in view, a hinge according to my invention comprises two similar leaves, each having a base for mounting it, a pintle carried by said base, and a knuckle carried by said base in spaced apart relation to said pintle. The knuckle is formed with a channel, the longitudinal axis of which aligns with the longitudinal axis of the pintle. The hinge and the method for hingedly connecting two members together, according to my invention, will be apparent after reference to the following detailed specification read in conjunction with the drawings.

In the drawings:

Figure 1 is a view showing two members about to be hingedly connected according to the present invention.

Figure 2 is a view showing the same two members hingedly connected.

Figure 3 is a sectional view showing the relation of the pintle and a co-operating knuckle immediately after they have been brought together.

Figure 4 is a sectional view showing the pintle and the knuckle after they have been rotated.

Referring to the drawings, a complete hinge according to my invention will be seen to comprise a leaf 10 and leaf 11 having bases 12 and 13 respectively for mounting them on the edges of members 14 and 15 that are to be hingedly connected together. The leaf 10 is similar to the

2

leaf 11 in construction and like numerals on each leaf refer to like parts in the portions of the specification that follow.

Each of the leaves will be seen to have a pintle 16 carried between spaced apart shoulders 17 and 18 which are supported by arms 19 and 20 on the base 12, and a knuckle 21 also supported by the arm 22 on the base 12. The knuckle 21 in the embodiment of the invention shown is formed with a channel 23 by bending the upper extremity of the arm 22 in a substantial U shape. The longitudinal axis of the channel 23 aligns with the longitudinal axis of the pintle 16 and the cross section of the channel 23 is designed to rotatably engage with the pintle 16 of a co-operating leaf. The shoulders 17 and 18 are spaced apart to snugly receive therebetween a knuckle of a co-operating leaf.

The method for connecting the members 14 and 15 together will be apparent from the drawings. The knuckle 21 and pintle 16 carried by the base 12 are mounted on the member 14 as shown, and the corresponding knuckle and pintle carried by the base 13 are mounted on the member 15. The members 14 and 15 are then rotated to cause the mouths of the channels 23 formed in each of the knuckles to face each other so that the leaves 10 and 11 can be brought into engagement with each other whereby to cause the knuckle of each leaf to engage with the pintle of the other. After the leaves have been so brought into engagement with each other, it is merely necessary to rotate one of the members with respect to the other. Upon rotation of the members 14 and 15 with respect to each other it will be apparent that the mouths of the channels formed in the knuckles 21 will no longer face each other, and that each channel will lock with the pintle it engages to prevent the two members from parting.

The channel 23 is formed with one of its sides extended as at 24 to aid the locking function of the knuckles.

In use stop means for preventing the members 14 and 15 from returning to the position in which the leaves 10 and 11 can disengage can be employed. It will further be apparent to those skilled in the art that the leaves could be designed by changing the angle of the channels 23 with respect to the bases so that they could be united when the members 14 and 15 are at any predetermined angle with respect to each other.

In the drawings I have shown a single leaf having the knuckle and pintle mounted on it. It will be apparent, however, that a separate leaf could be formed for the pintle and for the knuckle.

Embodiments of my invention other than the

one shown in the drawings will be apparent to those skilled in the art. I do not intend, therefore, that the scope of my invention should be limited by the foregoing specification except by the limitations expressed in the following claims. 5

What I claim as my invention is:

1. A hinge leaf, for co-operation with a similar hinge leaf, comprising a base having three spaced apart arms extending therefrom, the upper extremities of two of said arms that are adjacent each other being formed into shoulders, a pintle extending between said two shoulders, the upper extremity of the remaining arm being formed into a U shape to form a channeled knuckle, said channel having its longitudinal axis aligned with the longitudinal axis of said pintle, said shoulders being spaced apart to snugly receive therebetween a knuckle equal in length to the length of said above-mentioned knuckle, said channel formed in said first mentioned knuckle being designed to engage with a pintle having dimensions similar to said above-mentioned pintle. 15

2. A hinge leaf for co-operation with a similar hinge leaf to form a hinge, comprising a base for mounting said leaf, a pintle carried by said base, and a knuckle carried by said base in spaced relation to said pintle, said knuckle being formed with an open channel, the longitudinal axis of said channel being aligned with the longitudinal axis of said pintle, said channel 25

formed in said knuckle having a length that corresponds to the length of said pintle to engage with a pintle on a similar hinge leaf having a pintle dimension similar to said first mentioned pintle.

3. A hinge leaf for co-operation with a similar hinge leaf, comprising a base, two spaced apart shoulders carried by said base, a pintle extending between said two shoulders, a knuckle carried by said base, said knuckle being formed with a channel having its longitudinal axis spaced from and aligned with the longitudinal axis of said pintle, said shoulders being spaced apart to snugly receive therebetween a knuckle equal in length to the length of said above-mentioned knuckle, said channel formed in said knuckle being designed to engage with a pintle having dimensions similar to said above-mentioned pintle.
